[57] CLAIM

The ornamental design for a combined heat sealing machine and trimmer, as shown and described.

DESCRIPTION

FIG. 1 is a side elevational view of a combined heat sealing machine and trimmer showing my new design; FIG. 2 is a side elevational view of the side opposite that shown in FIG. 1;

FIG. 3 is a right end elevational view thereof;

FIG. 4 is a left end elevational view thereof;

FIG. 5 is a top plan view thereof;

FIG. 6 is a bottom right perspective view thereof; and

FIG. 7 is a bottom left perspective view thereof.
